TEMPERATURE COMPENSATOR FOR DYNAMO-ELECTRIC MACHINES

Application filed May 31, 1930. Serial No. 457,765.

The invention relates to control systems and especially to control systems for elevators.

As the art of elevators has developed, various improvements have greatly increased the efficiency of operation of the elevator systems over those of the earliest types. Among these improvements have been those designed to reduce the time required to complete certain operations such as accelerating and retarding the cars and stopping the same at landings. The performance of these operations by automatic means effects the greatest efficiency. This however requires uniform operation of the elevators.

Considerable difficulty has been experienced in high speed elevator systems due to the fact that as the field windings of the elevator hoisting motor become heated the resistance increases, thus cutting down the current flowing therethrough and increasing the speed of the motor for a given applied voltage. It has been determined that the field windings of the motors employed in high speed elevator systems heat up to their maximum temperature in about four hours. A temperature rise of eighty degrees Fahrenheit causes an increase of approximately twenty per cent in the resistances of the windings.

With a Ward Leonard system of control in which a direct current driving motor is employed, the resulting increase in speed is somewhat less in proportion than the increase in resistance, since as the generator field winding becomes heated its resistance increases, cuts down on the current flowing through said winding, weakens the generator field, and reduces the output voltage of the generator. This tends to reduce the elevator motor speed, thus partially compensating for the increased speed caused by the heating of the driving and elevator motor field windings. In spite of the partial compensation afforded by the heating of the generator field winding, the elevator speeds show an increase of ten per cent or more. This variation in speed has an undesirable effect on the control of the elevators.

It is important that the acceleration and re-

tardation of the elevator cars be regulated in such a way that no time is lost, and also that the levelling, or correction distance at the landing, does not vary too much. It has been found, particularly after the electrical apparatus has become heated, that quite long levelling cams are necessary, as otherwise, the cars will stop outside the levelling zone and will not level at the landing. It is necessary not only to use long cams for levelling but also to lengthen the time required for retarding the elevator by the main control, thus causing sluggish operation and loss of time, so that the elevators are not able to give the proper traffic handling capacity.

The principal object of this invention is to remedy the above difficulties and insure uniform speed operation of elevators.

One feature of the invention is to obtain practically uniform speed from an electrical unit regardless of the heating of its field windings.

Another feature of the invention is to obtain practically uniform speed of the elevator car from a combination of electrical drive units regardless of the heating of their field windings by the control of the current flowing through one or more of said field windings.

Other features and advantages will become apparent from the following description and appended claims.

The invention involves the controlling of the current flowing through one or more of the field windings of an elevator driving unit by employing variable resistances electrically connected with the field windings of the unit and changing the resistances with respect to time.

The time required to change the variable resistances from their upper to lower limits is made the same as that required for the field coils to become fully heated from a cold condition, and the resistances are made of such values that the field strength of the elevator motor remains constant. The variable resistances take the form of a motor driven rheostat the operation of which is initiated at the same time that the elevator is placed in service. The resistances are connected in

55

series with the fields of the driving unit and are so arranged that they are gradually short-circuited. The rheostat shunts the maximum resistance after about four hours travel of its movable contact in a forward direction and maintains this resistance short-circuited as long as the elevator is in service.

In the event that the elevator is shut down, the rheostat reverses and runs down to starting position in the same time that it consumed to shunt the maximum resistance. If the elevator is again placed in service after a short shut-down, the rheostat is started in the forward direction from a position at which it short-circuits nearly the same resistance that it did at the time of the shutdown. The rheostat action thus follows closely the heating and cooling of the field windings.

For the purpose of illustrating the genus of the invention typical concrete embodiments are shown in the accompanying drawings in connection with a Ward Leonard system of control.

Figure 1 is a diagram of an elevator control system embodying the invention;

Figure 2 is a diagrammatic representation of the control panel for the system illustrated in Figure 1 and showing the relation of the coils and contacts of various switches;

Figure 3 is a front elevational view of the motor driven rheostat shown diagrammatically in Figures 1 and 2;

Figure 4 is an end view of the device shown in Figure 3 with certain parts omitted;

Figure 5 is a fragmentary sectional view taken along the line 5-5 of Figure 3; and

Figure 6 is a diagrammatic view of a modified form of the invention applied to an alternating current drive.

No attempt is made in Figure 1 to show the coils and contacts of the various electromagnetic and other switches and associated parts in their related positions, a "straight" diagram being employed wherein the coils, contacts, and other parts are separated so as to render the circuits relatively simple. For a clearer understanding of the invention, the stationary contacts of the switches are illustrated in cross section.

The motor generator set employed comprises a driving motor 11, illustrated as of the direct current type, mechanically connected to drive a variable voltage direct current generator 12. The armature of the driving motor is designated 13, its series field winding 14, and its separately excited field winding 15. The armature of the generator is designated 16, its series field winding 17, and its shunt field winding 18. The series field winding 17 may have any desired number of turns so as to effect the proper compounding action of the generator. The elevator hoisting motor is designated as a whole by numeral 20, its armature being designated

21, and its separately excited field winding 22. A discharge resistance 23 is arranged in shunt with the generator separately excited field winding 18. Temperature compensating resistances 24, 25 and 26 are arranged in series with the separately excited field windings, 15 of the driving motor, 22 of the elevator motor, and 18 of the generator, respectively. Each of these resistances, 24, 25 and 26, is provided with a number of stationary contact blocks 27, numbered 1 to 10 inclusive, and is connected to said contact blocks by a desired number of selective taps 35. 28 designates movable contacts engaging the contact blocks 27 to cut out such portions of each resistance as desired.

A rheostat motor 29, having an armature 30, and reversing field windings 31 and 32, is provided for moving the contacts 28 to engage the several stationary contacts 27. The reversing field windings 31 and 32 are each provided with a discharge resistance 34 in shunt therewith. A resistance 33 is connected in series between the temperature compensating resistance 26 and the generator separately excited field winding 18. This single resistance 33, controlled in its action by accelerating switch coil F6 and a time relay reactance coil 36, illustrates only the last step of the accelerating means and may be indicative of any desired number of steps. 37 and 38 designate the direct current supply mains. M6 is the brake release coil for an electro-magnetic brake. This brake upon operation separates its back contacts M5 to insert a cooling resistance 40 in circuit with its coil M6. The car direction switch is designated as a whole by numeral 41. 42 is a safety switch in the car, and 43 and 44 are knife switches in the starting circuit. 45 designates a standing field resistance in the circuit for the elevator motor separately excited field winding 22 and its compensating resistance 25.

The electro-magnetic switches have been designated as follows:

A—potential switch
B—up direction switch
C—down direction switch
F—accelerating switch
G—maintaining relay
H—brake switch
K—starting switch
L—field control switch
M—brake release switch
R—starting relay
X—minimum current field relay
Y—rheostat limit switch
Z—speed regulating switch

Throughout the description which follows, these letters, in addition to the usual reference numerals, will be applied to the parts of the above enumerated switches. For example, B₃ are contacts on the up direction switch, while coil A₆ is the coil that operates the po-

tential switch. The electro-magnetic switches are shown in their deenergized positions.

- Referring to the starting operation of the driving motor, the start switch 44 is closed, 5 completing the circuit through the coil R_6 of starting relay R and through the knife switch 43. Relay R, upon operation, completes the circuit for coil K_6 of the starting switch K by closing contacts R_1 . Switch K on closing its 10 contacts K_1 and K_2 completes the circuit for the driving motor armature 13 and separately excited field winding 15, the contacts K_1 and K_2 being disposed one on each side of the line. These two contacts K_1 and K_2 of switch 15 K also complete the circuit for the elevator motor separately excited field winding 22 through the coil X_6 of the minimum current field relay, which coil X_6 is shunted by contacts L_5 of the field control switch L. At the 20 same time, switch K, closes its contacts K_4 to complete the circuit for the rheostat motor 30 through rheostat limit switch contacts Y_5 and reversing field winding 31, and opens its contacts K_5 to prevent the energization of the 25 other reversing field winding 32 of this motor. Switch K, through contacts K_3 , also connects the coil L_6 of the field control switch L across the driving motor armature. As the driving motor counter-E. M. F. builds up, switch L 30 on closing contacts L_1 operates to short-circuit the driving motor accelerating resistance, designated 39.
- The elevator motor separately excited field winding 22 has a resistance 45 in circuit 35 therewith. This resistance is of proper value to give the desired strength of the elevator motor field with the car at a standstill, usually referred to as a "standing" field. The coil X_6 of the minimum current field relay 40 X is also in series with the elevator motor separately excited field winding 22. The contacts X_1 of relay X, together with the contacts L_2 , in circuit with the coil A_6 of the potential switch A, and contacts L_5 of switch 45 L, in shunt to the coil X_6 of relay X, act to prevent the operation of the potential switch A and therefore cut off the supply of current to the generator field windings 17 and 18 until the driving motor 11 and generator 12 50 have come up to a certain speed and the elevator motor field has been built up to a certain value. This is to obviate runaway conditions when stopping and starting the driving motor. Switch A upon operation closes 55 its contacts A_1 and A_2 to supply current to the generator field windings 17 and 18 and at the same time opens back contacts A_5 to cut in a cooling resistance 19 in circuit with its coil A_6 .
- 60 The circuit for the potential switch A also passes through the safety switch 42 of the car and through the governor on the motor generator set, the contacts of said governor being designated 46. The purpose of the 65 governor is to break the circuits for relay R

and switch A and K in the event of overspeed of the driving motor 11.

To start the elevator car the car switch 41 is actuated to move contact bar 47 in a direction dependent upon the desired direction of car travel. Assuming up direction, contact bar 47 is moved so as to bridge contacts 48 and 49, completing the circuit for the up direction switch and brake switch coils B_6 and H_6 respectively, this circuit being through door contacts 51 and gate contacts 52. Only one pair of door contacts 51 are shown as indicative of all the door contacts connected in series relation. Switch B, upon operation, completes the circuit for the generator field by closing its contacts B_1 and B_2 . Switch H, upon operation, completes the circuit which energizes the brake release coil M_6 by closing contacts H_3 , short-circuits, by closing contacts H_1 , the standing field resistance 45 in series with the elevator motor separately excited field winding 22, and gives a strong field for starting. Upon further movement of the contact bar 47 to engage contact 50, a circuit is established for the coil F_6 of the accelerating switch F, subject to the contacts H_2 of switch H. The operation of switch F is delayed by the action of reactance coil 36 in circuit therewith. Switch F, upon operation, closes its contacts F_1 to short-circuit the resistance 33 in circuit with the generator separately excited field winding 18, and also separates its contacts F_5 arranged in shunt to the temperature compensating resistance 25 for the elevator motor separately excited field winding 22. This compensating resistance 25 remains short-circuited, however, until the generator voltage builds up to a certain value and contacts Z_5 are opened by speed regulating switch Z, the coil Z_6 of which is so connected as to be subject to the generator voltage.

Holding coils B_7 , C_7 and H_7 are provided for the direction switches and brake switch. In starting the car in the up direction, the circuit for the holding coils B_7 and H_7 of switches B and H is completed by contacts B_3 of switch B and contacts F_2 of switch F. As the generator field builds up, the current is sufficiently increased in its separately excited field winding 18 and in the coil G_6 of maintaining relay G to cause the operation of the relay, thus closing the contacts G_1 to bypass the contacts F_2 in the above holding circuit.

It is preferred further to provide the direction switches with a mechanical interlock to prevent their both being closed at the same time. Such an interlock may be in the form of a walking beam 55 pivotally mounted for engaging catches 56 and 57 on the armatures of the direction switches as shown in Figure 2. Upon operation of the up direction switch in response to the energization of its actuating coil B_6 , contacts B_1 , B_2 and B_3 engage

and contacts B_5 separate breaking the circuit leading to the actuating coil C_6 of the down direction switch.

To stop the car, the car switch 41 is turned to off position. Switch F drops out immediately, reinserting resistance 33 in circuit with the generator field winding 18 and short-circuiting the temperature compensating resistance 25 which is in circuit with the elevator motor separately excited field winding 22. The rate at which the generator field strength decreases is controlled by the discharge resistance 23 connected in parallel with the generator shunt field winding 18 and consequently the rate at which the current in the coil G_6 of the maintaining relay G, which is in circuit with the field winding 18, decreases is similarly dependent. Thus, although accelerating switch F opens its contacts F_2 in the above holding circuit for the direction switches and brake switch, this holding circuit is maintained established until relay G drops out and contacts G_1 separate. The brake switch and up direction switch are maintained in operated condition even though their operating coils are deenergized until the generator field strength has decreased to a certain value, and therefore until the generator voltage has decreased to a certain value. Upon the opening of the contacts G_1 of the relay G, switches B and H are permitted to drop out effecting the de-energization of the generator field winding 18 and the application of the brake, thus bringing the car to a stop.

Contacts designated 53 of a safety governor switch (not shown) are arranged in parallel with the resistances 45 and 25, which are in circuit with the elevator motor separately excited field winding 22, to effect the short-circuiting of these resistances in case of overspeed of the elevator car. Also, additional contacts H_5 are provided on the brake switch H for connecting the generator separately excited field winding 18 to the generator armature 16 upon the deenergization of said field winding. This is the usual suicide connection.

To stop the driving motor, the start switch 44 is turned to off position, deenergizing the starting relay R and consequently deenergizing starting switch K. Switch K dropping out, not only breaks the circuit for the driving motor but also causes a circuit to be completed for the rheostat motor 29 through its other reversing field winding 32 when contacts K_4 separate and contacts K_5 engage. This causes rotation of the rheostat motor in the opposite direction from that which occurred when the driving motor was started in operation. An adjustable resistance 54, in shunt to the rheostat motor armature 30, is provided for controlling the speed of this motor.

Referring particularly to Figures 3 and 4, a motor driven rheostat embodies the compensating resistances and the stationary contact blocks 27 which are shown diagrammatically in Figure 1. The rheostat is preferably mounted on an insulating panel 60 and comprises a motor 29, a speed reduction gear box 62, and a multiple resistance unit 63. The motor 29 is operatively connected to the gear box 62 and both are secured to the panel 60 by bolts 64. In order to secure the stationary contacts 27 to the panel 60 without interfering with the contact surfaces thereof, holes are drilled in the bottoms of the contact blocks and studs 65 threaded into said holes. Studs 65 project through the panel 60 and are provided with securing nuts 66 to fasten the contact blocks to the panel and to provide terminals for suitable resistance elements 67 which comprise the compensating resistances. Each of the resistance elements 67 has a plurality of taps 35 to allow a selection of the desired values of resistance for a particular installation or to vary the rate at which resistance is short-circuited, which may be desirable under certain conditions. This selection of values of resistance affords the same control of the compensation of each drive unit that could be effected by supplying each compensating resistance with an independently driven rheostat having means for controlling its speed.

The stationary contact blocks 27 are arranged in three parallel rows corresponding to rows of resistance elements 67 which make up each of the compensating resistances. A cross-head 68 carrying brush contacts 69 and a nut 70 is mounted so as to travel along the rows of stationary contacts. A screw 71 projecting from the reduction gear box 62 serves as the actuating and mounting means for the cross-head 68, said screw being threaded to the nut 70. A bearing member 72 bolted to the panel 60 is provided for the projecting end of screw 71. To the cross-head 68, there is secured substantially U-shaped support members 74, one leg of each being bolted to the cross-head and the other leg having an opening 75 therethrough and an inwardly directed forked end 76. The brush contact members 69, each having a normally disposed lug 78 at one end adapted to fit loosely the opening 75 and the other end curved to form a wiping contact portion 77 for engaging stationary contact blocks 27, are mounted in the support members 74. The lugs 78 and body portions of the contact members 69 are biased into the openings 75 and the forked ends 76 by springs 79 which are disposed between contact members 69 and the first mentioned legs of said support members. The cross-head 68 is provided with a stud 80 projecting therethrough and having one end threaded to the support members 74. Securing nuts 81 on the opposite ends of the studs

80 provide terminals for cables 82 which short-circuit that portion of the resistance between the end of the rheostat adjacent bearing 72 and the cross-head 68. A U-shaped channel 83, (see Figure 5), secured 5 to the panel 60 by flat-headed machine screws, cooperates with a stud 85 secured to the cross-head 68 to prevent rotation of said cross-head and uneven wear of the stationary and brush contacts.

The motor 29 has two fields, 31 for driving the same in a forward direction and 32 for driving it in the reverse direction. As the motor 29 drives the cross-head 68 in a forward direction, i. e. from the end adjacent the bearing 72 toward the reduction gear box 62, it causes the short-circuiting of more of the resistances 24, 25 and 26. The motor 29, gear reduction box 62, and screw 71 are so 15 designed that the complete forward travel of the cross-head 68 will consume about the same time that it takes for the field windings of the main motor 11, generator 12 and elevator motor 20 to become heated from cold condition to their maximum temperatures. Limit 20 switches 86 are disposed in the path of the cross-head 68 to break the power circuit to each of the reversing field windings 31 and 32 by opening one set of contacts Y5 and thus 25 stop the movement of the cross-head in either direction. The cross-head 68 then remains idle until the other field winding is excited causing the movement of the cross-head to the other limit or to an intermediate point 30 if the rheostat motor field windings are again reversed to cause reverse travel of the cross-head.

In the event that the motor-generator set is 35 shut down after complete forward travel of the cross-heads, which usually takes about four hours of continuous operation, the rheostat motor is reversed, as previously explained, and if the set is restarted a short time thereafter the cross-head is again reversed to move in a forward direction from a point in its travel at which nearly all of each of the compensating resistances 24, 25 and 26 is short-circuited.

It is obvious that a clock or other timing 40 device may be employed instead of the rheostat motor 29, which device would start when the motor-generator set starts and would reverse when the motor-generator set stops. Each compensating resistance may, if desired, be provided with a permanent shunt 45 resistance of such value as to prevent dangerous speeds being obtained if a rheostat brush should at any time fail to make contact.

Thus the short-circuiting of the compensating 50 resistances follows very closely the heating and cooling of the field windings of the motors and generators and as the resistance of these windings vary with their temperature, there is an inverse variation of 55 the compensating resistances. The current

through the field windings of the motors and generator is therefore maintained constant irrespective of the temperature of the windings and uniform operation of the elevators attained.

The positions of the stop switches 86 may be adjusted so as to stop the cross-head at more advanced or retarded points relative to the compensating resistances. To this end the switches are slotted as shown at 87 and 60 fastened to the panel 60 by bolts 88 to allow adjustment of the switches in the direction of travel of the cross-head 68. In this way the compensating resistances may be adjusted to correspond with different cold conditions of the motor and generator field windings which may be due to the seasonal temperatures, ventilation of machine rooms or other factors affecting the initial temperatures of the drive units.

In some direct current drive type installations it will be found, due to such factors as improper ventilation of machine rooms, insufficient capacity of drive units, and the like, that adequate compensation for the changes in resistance of the shunt field windings of the driving motor, generator and elevator motor cannot be obtained by cutting out resistance from their circuits. In such cases resistances may be added to, rather than cut out from, the circuit for the generator shunt field winding. This cuts down the current flowing through the generator shunt field winding, and weakens the generator field, and enables regulation of the output voltage of the generator so that uniform operation of the elevator motor is obtained. For example the shunt field winding of the driving motor may become so heated that its speed may considerably increase regardless of the resistance cut out by the motor driven rheostat. In such event the resistance added to the circuit of the generator separately excited field winding affords compensation to produce the desired output 95 voltage of the generator. To this end the connections to the compensating resistance 100 26 may be reversed so that resistance is cut in as the rheostat cross-head travels in a forward direction. In other installations compensating resistances may be electrically connected to but one shunt field winding, for instance to the generator shunt field winding, to give the desired regulation.

It is preferred, however, to reduce the compensating resistance in series with each field winding according to the embodiment first described since by this arrangement each unit retains the operating characteristics for which it was originally designed.

In Figure 6 there is illustrated a simplified layout of an alternating current drive embodying the invention. In this figure the drive units and timing device are indicated by legend and parts corresponding to those 130

previously described by primed characters. The compensating resistances 24', 25' and 26' in the A. C. drive system are in series with the field windings 58, 18' and 22'' of the exciter, the generator and the elevator motor, respectively. Y' designates contacts for limit switches actuated by the cross-head 68' as in the previously described arrangement. K' and K'' designate reversing switch contacts adapted to operate in connection with the starting and stopping of the motor-generator set. In this arrangement the speed of the driving motor is substantially constant, so that as the temperature of the exciter field windings and the generator separately excited field windings increases, resistance is cut out of both the circuit to the exciter field windings and that of the generator field windings. In this way the generator output voltage may be kept substantially constant if desired.

As many changes could be made in the above described arrangements, and many apparently widely different embodiments of this invention could be made without departing from the scope thereof, it is intended that all matter contained in the above description or showing shall be interpreted as illustrative and not in the limiting sense.

What is claimed is:

1. In combination, an elevator car, a hoisting motor therefor, a separately excited field winding for said motor, a source of current for said field winding, a resistance electrically connected to said field winding, and means operable at a predetermined rate for varying said resistance in such manner as to cause substantially the same amount of current to be supplied to said winding from said source during operation of said motor at a certain speed, regardless of the increase in resistance of said winding due to current flow therethrough.

2. In combination, an elevator car, a hoisting motor therefor, a separately excited field winding for said motor, a source of current for said field winding, resistance connected to said winding, and means operable at a rate commensurate with the rate of change in the value of the resistance of said winding incident to the flow and discontinuation of the flow of current therethrough for varying said resistance to maintain a uniform flow of current through said field winding.

3. In combination, an elevator car, a hoisting motor therefor, a field winding for said motor, a source of current for said winding, mechanism for connecting and disconnecting said winding to and from said source, and means operable at a predetermined rate and controlled by said connecting and disconnecting means for compensating for variations in the value of the resistance of said winding caused by temperature changes

thereof incident to the flow or discontinuation of the flow of current in said winding.

4. In combination, an elevator car, a hoisting motor therefor, a separately excited field winding for said motor, a source of current for said motor, means for controlling the supply of current from said source to said field winding, a rheostat in circuit with said field winding, a motor for operating said rheostat, and means responsive to said current controlling means for causing the operation of said rheostat operating motor to vary the resistance of said rheostat.

5. In combination, an elevator car, a hoisting motor therefor, a source of current, a switch for controlling the supply of current from said source to said motor, a resistance for controlling the operation of said motor, and means responsive to the closing of said switch for causing the variation of said resistance at a predetermined rate and responsive to the opening of said switch for causing the opposite variation of said resistance at a predetermined rate.

6. In combination, an elevator car, driving mechanism for said car, said mechanism comprising a dynamo-electric machine having a winding, a resistance for controlling the amount of current supplied to said winding, means for varying said resistance, means for starting and stopping said mechanism, and means dependent on said starting and stopping means for causing the variation of said resistance by said resistance varying means to be such as to compensate for variations in the value of the resistance of said winding incident to the flow and discontinuation of the flow of current therein.

7. In combination, an elevator car, driving mechanism for said car, said mechanism comprising a dynamo-electric machine having a winding, a resistance for controlling the amount of current to said winding, means for varying said resistance, and time controlled means for causing the variation of said resistance by said resistance varying means to be such as to compensate for variations in the value of the resistance of said winding incident to the amount and duration of the flow of current therein.

8. In combination, an elevator car, a hoisting motor therefor, a winding for controlling the operation of said motor, control mechanism for controlling the amount of current supplied to said winding, the amount of current flowing through said winding being dependent upon the operable condition of said control mechanism, and time controlled means for causing the amount of current flowing in said winding for each operable condition of said control mechanism to be substantially the same, regardless of changes in the resistance of said winding due to the flow or discontinuation of the flow of current therein.

9. In combination, an elevator car, a hoisting motor therefor, a generator for supplying current to said motor, means for driving said generator, a separately excited field winding for said motor, a separately excited field winding for said generator, a source of current for each of said field windings, and means for causing substantially uniform operation of the elevator car, regardless of variations in the value of the resistance of said field windings incident to the flow and discontinuation of the flow of current therethrough, said means comprising resistance connected to each of said field windings and time controlled means for varying said resistances.

10. In combination, an elevator car, a hoisting motor therefor, a generator for supplying current to said motor, means for driving said generator, a separately excited field winding for said motor, a separately excited field winding for said generator, a source of current for each of said field windings, a resistance in circuit with said generator field winding, a resistance in circuit with said motor field winding, and means controlled at a definite time rate for varying said resistances to compensate for the changes in the value of the resistance of said field windings incident to the flow and discontinuation of the flow of current in said field windings.

11. In combination, an elevator car, a hoisting motor therefor, a generator for supplying current to said motor, means for driving said generator, a separately excited field winding for said motor, a separately excited field winding for said generator, a source of current for each of said field windings, a resistance in circuit with said generator field winding, a resistance in circuit with said motor field winding, and time controlled means for varying said resistances in such manner as to cause the same current to be supplied to said motor field winding and the same voltage to be generated by said generator for each operation of the elevator car at full speed, irrespective of variations in the resistance of said field windings due to temperature changes caused by the flow and discontinuation of the flow of current through said windings.

12. In combination, an elevator car, a hoisting motor therefor, a generator for supplying current to said motor, driving means for said generator, a separately excited field winding for said motor, a separately excited field winding for said generator, a source of current for each of said field windings, means for starting said driving means in operation, a rheostat having a plurality of resistances, one in circuit with each of said field windings, and means responsive to the starting of said driving means for causing the operation of said rheostat to vary each of said resistances.

13. In combination, an elevator car, a hoisting motor therefor, said hoisting motor having a field winding, a generator for supplying current to said motor, said generator having a field winding, substantially constant speed driving means for said generator, an exciter driven by said driving means, said exciter having a field winding, a plurality of resistances, one in circuit with each of said field windings, means for causing substantially uniform operation of said elevator car, said last-named means comprising time controlled means for varying each of said resistances in such manner as to compensate for the variations in the value of the resistance of the field winding for which such resistance is provided.

14. In combination, an elevator car, a hoisting motor therefor, said hoisting motor having a field winding, a generator for supplying current to said motor, said generator having a field winding, substantially constant speed driving means for said generator, an exciter driven by said driving means, said exciter having a field winding, a rheostat having a plurality of resistances, one in circuit with each of said field windings, and means responsive to the starting of said driving means for causing the operation of said rheostat to vary each of said resistances.

15. In combination, an elevator car, a hoisting motor therefor, said hoisting motor having a field winding, a generator for supplying current to said motor, said generator having a field winding, substantially constant speed driving means for said generator, an exciter driven by said driving means, said exciter having a field winding, means for starting and stopping said driving means, a rheostat having a plurality of resistances, one in circuit with each of said field windings, means responsive to the starting of said driving means for causing the operation of said rheostat to vary each of said resistances, and means responsive to the stopping of said driving means for causing the operation of said rheostat to oppositely vary each of said resistances.

16. In combination, an elevator car, a hoisting motor therefor, a generator for supplying current to said motor, driving means for said generator, a separately excited field winding for said motor, a separately excited field winding for said generator, a source of current for each of said field windings, means for starting said driving means in operation, a rheostat having a plurality of resistances, one in circuit with each of said field windings, means for operating said rheostat at a predetermined rate, means responsive to the starting of said driving means for causing the operation of said rheostat by said operating means in a certain direction to vary each of said resistances, and means for stopping the operation of said rheostat by said oper-

ating means after continuous operation thereof in said certain direction for a predetermined time after it has been started in operation.

17. In combination with an elevator car, an elevator motor, a generator for supplying current to said elevator motor, a driving motor for operating said generator, a separately excited field winding for each of said 10 motors and said generator, a source of current for said field windings, means for starting the operation of said driving motor, and means operable in response to the operation of said starting means to compensate for variations in the resistance of the field windings due to heating of the windings incident to the flow of current therein.

18. In combination, an elevator car, a hoisting motor therefor, a generator for supplying current to said motor, a driving motor for said generator, a separately excited field winding for each of said motors and said generator, a source of current for each of said field windings, a resistance connected to each 25 of said field windings, and time controlled means for varying said resistances in such manner as to provide substantially uniform operation of the elevator car, regardless of variations in the resistance of any of said 30 field windings due to the flow or discontinuation of the flow of current therein.

19. In combination, an elevator car, a hoisting motor therefor, a generator for supplying current to said motor, a driving motor for 35 said generator, a separately excited field winding for each of said motors and said generator, a source of current for each of said field windings, means for starting and stopping said driving motor, a rheostat having a plurality of resistances, one in circuit with each of said field windings, means responsive to the starting of said driving motor for causing the operation of said rheostat to vary each of said resistances, and 40 means responsive to the stopping of said driving motor for causing operation of said rheostat to oppositely vary each of said resistances.

20. In combination, an elevator car, a 50 hoisting motor therefor, a generator for supplying current to said motor, a driving motor for said generator, a separately excited field winding for each of said motors and said generator, a source of current for each 55 of said field windings, means for starting and stopping said driving motor, a rheostat having a plurality of resistances, one in circuit with each of said field windings, a motor for operating said rheostat to vary each of 60 said resistances, and means responsive to the starting of said driving motor for causing operation of the rheostat operating motor in one direction to vary each of said resistances and responsive to the stopping of said driving 65 motor for causing the operation of the

rheostat operating motor in the opposite direction to oppositely vary each of said resistances.

21. In combination, an elevator car, a hoisting motor therefor, a generator for supplying current to said motor, means for driving said generator, a separately excited field winding for said motor, a separately excited field winding for said generator, a source of current for each of said field windings, means for starting and stopping said driving means, a rheostat having a plurality of resistances, one in circuit with each of said field windings, means for operating said rheostat, and means responsive to the starting of said driving means for causing the operation of said rheostat by said operating means in a certain direction from a predetermined point to vary each of said resistances and responsive to the stopping of said driving means for causing the operation of said rheostat by said operating means to return it to said predetermined point to oppositely vary each of said resistances, said operating means causing operation of said rheostat at the same rate in either direction so that in case the driving means is restarted before the rheostat is returned to said predetermined point, said operating means is caused to reverse the operation of said rheostat at the point to which it has been moved at the time that the restarting of the driving means is effected. 70 75 80 85 90 95

22. In combination, an elevator car, a hoisting motor therefor, a generator for supplying current to said motor, driving means for said generator, a separately excited field winding for said motor, a separately excited field winding for said generator, a source of current for each of said field windings, means for starting and stopping said driving means, and means for causing substantially uniform operation of said hoisting motor, said last-named means comprising a rheostat having a plurality of resistances, one in circuit with each of said field windings, means for operating said rheostat and means responsive to the starting of said driving means for causing the operation of said rheostat by said operating means to vary each of said resistances to compensate for increases in the value of the resistance of each of said field windings and responsive to the stopping of said driving means for causing the operation of said rheostat by said operating means in the opposite direction to oppositely vary each of said resistances to compensate for decreases in the value of the resistances of each of said field windings, said operating means operating said rheostat at the same rate in either direction so as to provide proper compensation for the changes in resistance of said field windings in case of short periods of shut-down of said driving motor. 100 105 110 115 120 125 130

23. In combination, an elevator car, a hoisting motor therefor, a generator for supply-

ing current to said motor, a driving motor for said generator, a separately excited field winding for each of said motors and said generator, a source of current for each of 5 said field windings, means for starting and stopping said driving motor, a rheostat having a plurality of resistances, one in circuit with each of said field windings, a motor for operating said rheostat to vary each of said 10 resistances, means responsive to the starting of said driving motor for causing operation of the rheostat operating motor in one direction to vary each of said resistances and responsive to the stopping of said driving motor 15 for causing the operation of the rheostat operating motor in the opposite direction to oppositely vary each of said resistances, said rheostat having limiting positions of operation, and means for stopping said rheostat operating motor upon said rheostat reaching 20 either of said limiting positions.

In testimony whereof, we have signed our names to this specification.

LEE IRWIN DAVIS.
